(57) **CLAIM**

The ornamental design for an umbrella, as shown and described.

DESCRIPTION

FIG. 1 is a top, front, right perspective view of an umbrella showing my new design;

FIG. 2 is a top view thereof;

FIG. 3 is a front view thereof, with the back view being a mirror image;

FIG. 4 is a bottom plan view thereof; and,

FIG. 5 is a right view, with the left view being a mirror image. In the drawings, the broken lines depict unclaimed subject matter only and form no part of the claimed design.
